UNITED STATES PATENT OFFICE.

CHARLES GREEN, JR., OF KINGS CROSS, LONDON, ENGLAND.

MACHINE FOR FACILITATING THE TRIMMING OF WALL-PAPER.

1,143,187.

Specification of Letters Patent. Patented June 15, 1915.

Application filed April 19, 1913. Serial No. 762,281.

To all whom it may concern:

Be it known that I, CHARLES GREEN, Jr., engineer, a subject of the King of Great Britain, residing at 21 Northdown street, 5 Kings Cross, London, England, have invented certain new and useful Improvements in Machines for Facilitating the Trimming of Wall-Paper, and of which the following is a specification.

10 This invention refers to apparatus for attachment to a machine for printing wall-papers, through which apparatus the paper before it has been printed is caused to travel, and by passing between grooving rollers set 15 at the required distance apart, grooves are impressed on opposite sides of the paper at a distance apart corresponding with the pattern to be printed on the paper and so as to leave the unprinted edges of the paper that 20 is, the list or trimmings, outside the said grooves.

Now in machine-printed wall-papers the pattern is not always printed in an exactly central position on the roll of paper, the result being that the unprinted edge or list 25 varies in width, sometimes being wider on one side of the printed pattern than on the other, and therefore to fulfil the requirement of grooving the paper always at the 30 edges of the pattern about to be printed, means are provided, according to this invention, for the simultaneous lateral adjustment of the set of grooving rollers or disks relatively to the wall-paper while the 35 machine is running, and the said grooving rollers are so laterally adjusted by a hand controlled mechanism; thus the grooving rollers are always made to correspond with the edges of the pattern being printed. Moreover it is also desirable that convenient 40 means should be provided by which the operator can at any time desired throw the grooving rollers into and out of operation.

The object therefore of the present invention is to provide an improved construction of apparatus or machine, and by which the before mentioned requirements are efficiently carried out, and the said invention will now be described with reference to the accompanying drawings.

Figure 1 shows in two portions a sectional front elevation of the apparatus applied to the frame of a wall-paper printing machine, and Fig. 2 is a sectional end view of the 55 said apparatus, Fig. 3 being a detail in plan hereafter referred to.

A portion of a frame 1 of a wall-paper printing machine is shown at Fig. 1, to which two brackets 2, 3 are attached. One of these brackets 2 is formed with guides 4 on which an adjustable standard 5 is carried, while a similar standard 5^x is fixed to or formed with the bracket 3. The adjustment of the said standard 5 to the right or left is effected by means of a screw-threaded shaft 6, carried in the standard 5^x and engaging with its screw thread in a correspondingly screw-threaded bearing or nut in the standard 5; the lateral adjustment shaft 6 is fitted at each end with a hand wheel 6^x, 70 by which it can be rotated and thereby vary the distance of the standard 5 from the standard 5^x. The standards 5, 5^x carry in bearings two shafts 7 and 8, which in their turn carry the grooving rollers 9 and 10, and 75 11 and 12, the edges of which are held together with a pressure which may be adjusted by mechanism now about to be described.

The bearings of the shaft 8, carrying the 80 lower set, in this instance, of grooving rollers 11, 12, are slidable in guides in the standards 5, 5^x, and immediately below the axis of the shaft 8 is a shaft 13 also carried in bearings in the standards 5, 5^x. The shaft 85 13 is fitted with eccentrics 14, 15, the eccentric 14 being revoluble with the shaft 13 by means of a feather and groove, so that the said shaft 13 can slide endwise through the standard 5^x and accompanies the lateral adjustment of the standard 5, being fitted on each side of the bearing in that standard 90 with collars.

Vertical sliding bearings 16, 17 for the shaft 8 carry adjustment screws 18, 19, the 95 heads of which rest upon the eccentrics 14, 15 respectively. The pressure adjustment shaft 13 is fitted at one end with means by which it can be given the necessary angular adjustment, such as with a lever 20, to cause 100 the separation or bringing together of the grooving rollers 9, 10, 11 and 12.

The width between the grooving rollers 9 and 11 and 10 and 12 is regulated by a screw adjustment 21 working in conjunction with a screw thread on the shaft 7, the said screw adjustment moving a sleeve 22 to which the grooving roller 9 is attached, and which sleeve 22 carries a projecting flange 23, which takes between two collars 24 carried on a sleeve 25 on which the grooving roller 11 is supported. The sleeves 22 and 110

25 are carried upon feathers and grooves on their respective shafts 7 and 8, so that they can be adjusted endwise thereon but must accompany the revolving motion of the 5 said shafts.

The paper to be grooved is shown in the dot and dash lines at 26 in Fig. 2, and it will be seen that it passes over a guiding roller 27 and under a guiding roller 28, and between 10 these two rollers it passes between the grooving rollers.

The shafts 7 and 8 are driven at a uniform speed by means of spur wheels 29 and 30, by a belt wheel 31, shown by way of example, 15 or by gearing.

When the apparatus is at work and the wall-paper is passing through the grooving apparatus to the printing machine, the grooving rollers are rotated and impress 20 deep grooves from opposite sides into the paper in such positions as to register with the edges of the pattern to be printed thereon, and if these grooves show the least sign of leaving the desired path, one of the hand 25 wheels 6^x is turned, which traverses the standard 5, the latter carrying with it the shafts 7 and 8 and the shaft 13, but not moving laterally the rollers 27 and 28, the standard 5 sliding over the spindles of the 30 said rollers. One of the rollers 28 for example, is shown at Fig. 3 where one spindle end 28^x is capable of sliding through its bearing in the laterally adjustable standard 5, while the other spindle end is held by 35 collars in its bearing in the standard 5^x.

A little practice soon enables the operator to keep the grooving rollers or disks running steadily upon the exact line where it is desired to groove the paper. Paper grooved 40 in this way is sold in the piece, and the unprinted edges protect the piece from injury either from light, damp or other cause. They also protect the paper during the pasting operation. The tearing off of the strip 45 leaves a beveled edge on the paper, which is especially suitable for abutting against the edge of the next piece of paper which is to be applied adjacent to it.

50 What I claim as my invention and desire to secure by Letters Patent is:—

1. Apparatus for grooving wall-paper as it enters the printing machine to facilitate the trimming thereof; comprising two pairs of 55 grooving rollers between which the paper passes; two parallel shafts carrying said rollers; standards in which bearings for the opposite ends of said shafts are provided, brackets on the frame of said printing machine to support said standards, traversing means operative on one of said standards to adjust it nearer to or farther from the other and stationary standard, means to prevent endwise movement of said shafts in the bearings in said adjustable standard, means to

allow of endwise movement of said shafts in the bearings in the stationary standard and driving mechanism to rotate said shafts and grooving rollers.

2. Apparatus for grooving wall-paper as it enters the printing machine to facilitate the trimming thereof; comprising two parallel shafts, two grooving rollers on each shaft and rotatable therewith the grooving rollers on one shaft coacting with the grooving rollers on the other shaft, standards at opposite ends of said shafts, brackets on the frame of said printing machine to carry said standards, stationary bearings in said standards for one of said shafts, adjustable 80 bearings in said standards for the other of said shafts, means operative independently upon each of said adjustable bearings to adjust the same toward and away from said stationary bearings to regulate the distance 85 between the grooving rollers and driving mechanism to rotate said shafts.

3. Apparatus for grooving wall-paper as it enters the printing machine to facilitate the trimming thereof; comprising an upper and a lower parallel shaft, standards at opposite ends of said shafts, brackets on said printing machine to carry said standards, stationary bearings in said standards for said upper shaft, vertically adjustable bearings in said standards for said lower shaft, means for adjusting either of said bearings independent of the other, a grooving roller fixed to each of said shafts and opposite each other, a second grooving roller on each of said shafts, said latter rollers being located opposite each other and capable only of longitudinal movement on said shafts, means in connection with one of said shafts to effect the longitudinal movement of said 105 grooving roller, means for simultaneously moving the corresponding grooving roller on the other shaft, and driving mechanism for rotating said parallel shafts.

4. Apparatus for grooving wall-paper as it enters the printing machine to facilitate the trimming thereof; comprising an upper and a lower parallel shaft, two grooving rollers on each shaft and rotatable therewith the grooving rollers on one shaft coacting with the grooving rollers on the other shaft, standards at opposite ends of said shafts, brackets on the frame of said printing machine to carry said standards, stationary bearings in said standards for the upper shaft, vertically movable bearings in said standards for said lower shaft, reciprocatory means carried by said standards and operative simultaneously upon said movable bearings to effect the movement of said lower shaft in a direction perpendicular to the axis of said upper shaft, and driving mechanism to rotate said upper and lower shafts.

5. Apparatus for grooving wall-paper as

it enters the printing machine to facilitate the trimming thereof; comprising two pairs of grooving rollers between which the paper passes, two parallel shafts carrying said 5 rollers, standards in which bearings for the opposite ends of said shafts are provided, brackets on the frame of said printing machine to support said standards, traversing means operative on one of said standards to 10 adjust it nearer to or farther from the other and stationary standard, means to prevent endwise movement of said shafts in the bearings in said adjustable standard, rotatable guiding rollers carried in bearings in 15 said standards to guide the paper to and from said grooving rollers, means to prevent longitudinal movement of said guiding rollers in said stationary standard and driving mechanism to rotate said shafts and 20 grooving rollers.

6. Apparatus for grooving wall-paper as it enters the printing machine to facilitate the trimming thereof; comprising a bracket on the frame of the printing machine, a

standard fixed to said bracket, a second 25 bracket on said frame, guides on said second bracket, a standard adjustable on said guides to and from said fixed standard, a screw-threaded shaft, bearings in said brackets to support said shaft the screw 30 thread of which engages a screw-threaded aperture in said adjustable standard, means for imparting rotary movement to said screw-threaded shaft to cause the traversing of the said adjustable standard on its guides, 35 two parallel shafts carried in bearings in said standards, means to prevent longitudinal movement of said shafts in the bearings in the adjustable standard, two pairs of co-acting grooving rollers on said shafts and 40 driving mechanism to rotate said shafts and grooving rollers.

In witness whereof I have hereunto set my hand in the presence of two witnesses.
